RAZOR BLADE SHARPENER

Albert Aurili, Palm Beach, Fla., assignor of
one-half to Chauncey C. Woodworth, Palm
Beach, Fla.

Application May 31, 1933. Serial No. 673,764

2 Claims. (Cl. 51—212)

This invention appertains to new and useful improvements in sharpeners for razor blades, and more particularly to a simple and inexpensive device which can be readily carried about or incorporated in a razor handle and which can be employed without inconvenience to the user.

Other important objects and advantages of the invention will become apparent to the reader of the following specification.

10 In the drawing:—

Figure 1 represents a side elevational view of the device.

Figure 2 represents a vertical sectional view through the device, as represented in Figure 1.

15 Figure 3 represents a top plan view of the device.

Figure 4 represents a sectional view taken substantially on line 4—4 of Figure 1.

20 Figure 5 represents a side elevational view of the sharpening device embodied in a razor handle, the same being shown in open position.

Referring to the drawing wherein like numerals designate like parts, it can be seen in Figure 1, that numeral 5 represents a base having a reduced core extension 6, as shown in Figure 2, which extends upwardly into the lower portion of the elongated upstanding barrel 7. Thus the barrel is supported in a vertical position and this barrel, as shown in Figure 2, is provided with a pair of slots 8—8 therein at diametrically opposite side portions and through these slots a razor blade 9 can be disposed and reciprocated with the edge to be sharpened resting in the crotch 10 formed by a pair of crossed steel spindles 11—11, the lower ends of which are anchored in the said core 6, while their upper ends are sprung

into notches 12—12 in the upper inner side portions of the said barrel 7. (See Figure 3.)

As shown in Figure 5, this sharpener can be embodied in a razor handle 13 by making the razor handle hollow to receive the bifurcated barrel 7^a which is pivotally connected to the handle 13, as at 6^a. The crossed spindles 11^a—11^a can be mounted in this barrel 7^a in any suitable manner, preferably in the manner shown in Figure 2, so that the crossed portions of the spindles will be exposed where they can be easily reached by the blade to be sharpened.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

1. A razor blade sharpener comprising a hollow bifurcated member and a pair of hard members fixed in crossed relation within the bifurcated hollow member with their crossed portions exposed at the bifurcated portion of the hollow member and a plug in the opposite end of the hollow body in which the adjacent ends of the hard members are anchored.

2. In combination, a razor handle, a tubular member swingably connected to the handle, said handle being hollow to receive the tubular member, and edge forming members disposed in the said hollow member and adapted to be engaged by a razor blade to be sharpened.

ALBERT AURILI.
